UNITED STATES PATENT OFFICE

2,256,850

SNAP FASTENER

Forrest G. Purinton, Waterbury, Conn., assignor
to The Patent Button Company, Waterbury,
Conn., a corporation of Connecticut

Original application March 17, 1941, Serial No.
383,813. Divided and this application March
27, 1941, Serial No. 385,553

5 Claims. (Cl. 24—208)

My invention relates to new and useful improvements in snap fasteners, and is a division of the application filed by me on March 17, 1941, Serial Number 383,813, for Snap fasteners.

The present invention relates to what is known as a clamping member or ring, and has for an object to provide a means to receive and hold the prongs of the socket member of the snap fastener when the said socket is attached to its cloth.

Another object of the invention is to provide the ring or clamping member to which, and forming part thereof, is molded a plastic, such as "plaskon," which may be of any desired color so as to harmonize with the garment to which the snap fastener is to be attached.

Another object of the invention is to provide the ring of the socket member of the snap fastener with means for receiving the attaching prongs of the socket member and supporting a head formed of Plaskon, which is so anchored in the said ring that there is no possibility of the same ever becoming accidentally removed therefrom.

Still another object of the invention is to provide a ring member for a snap fastener which will not only receive and tightly hold the prongs of the socket member, but will also provide a very pleasing and harmonizing appearance for the garment to which the ring is attached and further will prevent the cloth or fabric from stretching during the attaching operation.

With these and other objects in view, the invention consists in certain new and novel arrangements and combination of parts, as will be hereinafter more fully described and pointed out in the claims.

Referring now to the drawing showing a preferred embodiment,

Fig. 1 is a sectional view of the metal ring;

Fig. 2 is a similar view but showing the Plaskon head or top molded in place;

Fig. 3 is a top plan view of the ring with its embedded Plaskon, a part being broken away for the sake of clearness of illustration;

Fig. 4 is a bottom plan view thereof; and

Fig. 5 is a sectional view of the ring with the socket member in its attached position, the dotted lines showing the socket before being clamped by the ring.

Referring now more specifically to the drawing and for the moment to Fig. 1, there may be seen the metal ring 1 preferably formed of brass having the overhanging and downwardly extending wall 2 and the outwardly extending peripheral

rim 3, which latter terminates short of the inner surface of the overhanging wall 2. This overhanging wall 2 and the peripheral rim 3 are integral with the body 4 of the ring.

5 There may also be seen the inner peripheral bead 5, the purpose of which is to be shortly explained.

Rather than having a conventional open ring, I provide a plastic insert or head 6, which may 10 be clearly seen in Fig. 2. Preferably this is a urea formaldehyde composition, such as Plaskon, and may be translucent or opaque and may be of different colors to harmonize with the garment to which it is to be secured.

15 It might be mentioned here that Plaskon has a high water absorption factor and a half-inch disk may shrink as much as fifteen thousandths of an inch. However, by forming the mold (not shown) so that the Plaskon disk 6 will overlie a portion of the ring, such as at 7, and underlie the bead, as at 8, the Plaskon is well anchored 20 with respect to the ring. Thus, even though the Plaskon may swell or shrink, it can never become detached from about the anchoring bead 5.

25 It is also to be noticed that the under surface of the Plaskon head tapers slightly near its outer under periphery, as at 9, to the horizontal under surface of the top, as at 10. I form the head in this manner so that the cloth 11 (Fig. 5) when gripped between the socket member 12 and its ring 1 will not be forced too far upwardly, which would tend to stretch the material about the ring and cause the cloth to pucker.

In other words, the topmost position of the 30 cloth 11 is about in a plane with the top of the metal ring 1 and will thus lie snugly against the under surface of the Plaskon disk 6 when the ring and socket member are attached.

In Fig. 5, there is shown a fragmentary portion of the cloth 11 and a socket member 12, which latter is provided with the prongs 13, which are to be gripped within the ring member. The socket member is disclosed in detail in the 35 parental application heretofore mentioned.

45 Briefly, it consists of a circular metal plate having the prongs 13, the depressed portions 14 of the metal, the spring fingers 15, and the guards 16, the spring fingers 15 being adapted to grip the male member (not shown) of the socket.

50 When the socket member of the snap fastener is being attached, the prongs 13 will pierce the cloth 11 and impinge on the under surface of the overhanging wall 2 of the ring 1 and be bent to the position as shown in Fig. 5 to thus firmly 55 hold the socket and its ring to the cloth.

The ring with its plastic insert or head of desired color will provide a snap fastener pleasing in appearance, and the color may harmonize with the color of the garment to which it is to be attached.

Furthermore, the plastic head will prevent too great a stretching of the cloth within the ring during the attaching operation and will also tend to strengthen the ring.

Although I have mentioned "plaskon," it will be understood that I can use the more expensive Bakelite or any other desired plastic, if so desired.

Finally, it will also be understood that the plastic head may be greater in diameter or of greater thickness than shown in the drawing, if found desirable.

Having thus described my invention, what I claim as new and desire to secure by Letters Patent is:

1. In a socket for a snap fastener, a clamping ring having an upper outwardly and downwardly overhanging wall; an integral lower peripheral rim spaced beneath said wall and stopping short of the periphery of said wall to thereby form a space for the prongs of a socket member, a plastic head extending over the center of said ring, inner peripheral projecting means formed at the top of said ring, and the said plastic head anchored in position by said aforementioned means. 30

2. A clamping ring for a snap fastener socket, said ring having a lower horizontally extending rim and a spaced outwardly and downwardly overhanging wall and the space between the said rim and said wall adapted to receive the prongs of a snap fastener socket, a plastic head on said ring and extending slightly below the top surface

of said ring and also overhanging the upper inner peripheral surface of the said ring, and inner peripheral anchoring means formed integral with the ring and embedded within said plastic head to hold the same tightly in position.

3. A clamping ring for a snap fastener socket, said ring having a horizontally outwardly extending lower peripheral rim and an upper downwardly extending overhanging wall to thereby provide a receptive space for the prongs of a socket member, the ring provided with an upper inner peripheral integral bead, a head on said ring and the under surface of the head tapering downwardly to a plane beneath said bead, the outer upper peripheral edge of the head overlying said bead whereby the head is anchored to said ring and the upper inner surface of the head being substantially in a horizontal plane with said bead.

4. A clamping ring for a snap fastener socket, said ring having spaced outwardly extending rims, one of which is longer than the other, to thereby provide a directing wall and a receptive space for the prongs of a socket member, a plastic head on said ring, means formed on the inner peripheral surface of the ring for interlocking with and anchoring the said head tightly within the ring and the plastic head being thickest near its outer peripheral edge.

5. A plastic head having a metal ring embedded therein and the said ring provided with an overhanging wall and a spaced underlying rim, the said wall and rim projecting beyond the side walls of the plastic head, and the said space between the wall and the rim adapted to receive and hold the prongs of the socket member of a snap fastener.

FORREST G. PURINTON.
